[57] CLAIM

The ornamental design for a adjustable table lamp, as shown and described.

DESCRIPTION

FIG. 1 is a top, front, right side perspective view of an adjustable table lamp showing my new design;

FIG. 2 is a front elevation view thereof;

FIG. 3 is a left side elevation view thereof;

FIG. 4 is a top plan view thereof;

FIG. 5 is a rear elevation view thereof;

FIG. 6 is a bottom plan view thereof.

The electric cord in FIGS. 1, 3, 4, and 6 and the lamp bulb structure inside the reflector in FIG. 6 are shown in broken lines for illustrative purposes only.

FIG. 2

FIG. 3

FIG. 4

FIG. 5

FIG. 6
